(57) **CLAIM**

The ornamental design for a combined plenum, seal and clip module for patient interface, as shown and described.

DESCRIPTION

FIG. 1 is a perspective view of a combined plenum, seal and clip module showing a first embodiment according to our new design;

FIG. 2 is an enlarged perspective view thereof in isolation;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof;

FIG. 9 is another perspective view thereof;

FIG. 10 is a perspective view of a combined plenum, seal and clip module showing a second embodiment according to our new design;

FIG. 11 is an enlarged perspective view thereof in isolation;

FIG. 12 is a front view thereof;

FIG. 13 is a rear view thereof;

FIG. 14 is a top view thereof;

FIG. 15 is a bottom view thereof;

FIG. 16 is a right side view thereof;

FIG. 17 is a left side view thereof; and,

FIG. 18 is another perspective view thereof.

The broken line showing of the patient interface in FIGS. 1 and 10 illustrates the environment of the claimed design and forms no part thereof.

Line shading and stippling in FIGS. 1-9 have been used to indicate a contrast in appearance.
